US00D998324S

(12) **United States Design Patent** (10) **Patent No.:** **US D998,324 S**
Natsume et al. (45) **Date of Patent:** **** Sep. 12, 2023**

(54) **BELT ASSEMBLY WITH HOLDERS AND DEVICES**

(71) Applicant: **Magic Leap, Inc.**, Plantation, FL (US)

(72) Inventors: **Shigeru Natsume**, Weston, FL (US); **Sebastian Gonzalo Arrieta Gunther**, Fort Lauderdale, FL (US)

(73) Assignee: **Magic Leap, Inc.**, Plantation, FL (US)

(**) Term: **15 Years**

(21) Appl. No.: **29/723,305**

(22) Filed: **Feb. 5, 2020**

(51) **LOC (14) Cl.** **03-05**

(52) **U.S. Cl.**

USPC **D3/215**

(58) **Field of Classification Search**

USPC D3/201, 215, 218, 224, 226, 228, 318, D3/323, 324; D11/200, 201; D2/627, D2/629

(57) **CLAIM**

The ornamental design for a belt assembly with holders and devices, as shown and described.

DESCRIPTION

FIG. 1 is a top perspective view of the belt assembly with holders and devices.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines illustrate environmental features that form no part of the claimed design.

1 Claim, 4 Drawing Sheets
